MOBILE UTILITY RACK

David Harper, Pittsburgh, Pa.

Application March 27, 1959, Serial No. 55,217.

Term of patent 14 years

(Cl. D33—14)

Figure 1 is an isometric view of a mobile utility rack, as viewed from the front; and

Figure 2, a similar view, as viewed from the front and side.

I claim:

The ornamental design for a mobile utility rack, as shown.
